UNITED STATES PATENT OFFICE

150,491

DESIGN FOR A SERVICE STATION

Hobert C. Brown, Amarillo, Tex.

Application August 23, 1946, Serial No. 132,788

Term of patent 3½ years

(Cl. D13—1)

To all whom it may concern:

Be it known that I, Hobert C. Brown, a citizen of the United States, residing at Amarillo, in the county of Potter and State of Texas, have invented a new, original, and ornamental Design for a Service Station, of which the following is a specification, reference being had to the accompanying drawing, forming part thereof.

The figure is a perspective view of a service station, showing my new design.

Side of the service station not shown corresponds substantially to the side illustrated, and the rear wall is essentially a plain surface.

I claim:

The ornamental design for a service station, as shown and described.

HOBERT C. BROWN.
